ELECTRIC CAR LIGHTING COMPANY, OF MILWAUKEE, WISCONSIN,
A CORPORATION OF WISCONSIN.

TRAIN-LIGHTING SYSTEM.

No. 799,527.

Specification of Letters Patent.

Patented Sept. 12, 1905.

Application filed April 24, 1905. Serial No. 257,141.

To all whom it may concern:

Be it known that I, WILLIAM L. BLISS, a citizen of the United States, residing at Brooklyn, in the county of Kings and State of New York, 5 have invented new and useful Improvements in Train-Lighting Systems, of which the following is a full, clear, concise, and exact description, reference being had to the accompanying drawing, forming a part of this specification.

The present invention relates to improvements in lighting systems which are especially adapted to be employed for lighting cars or other units of transportation by electricity.

15 The particular form of system to which the present invention relates is especially adapted to be employed for lighting a train of cars. Each car in the train is equipped with a storage battery and lamps, and a single generator, 20 which is driven by an axle or similar means, furnishes current to all of the cars.

The present application sets forth and claims a modification of an invention which is disclosed in an application filed by me June 16, 25 1904, Serial No. 212,835.

According to the present invention an automatic rheostatic device or variable resistance is employed to regulate the generator, so as to confine the output thereof within pre- 30 arranged limits notwithstanding its wide variations in speed.

It is the object of the present invention to provide means which will prevent the automatic rheostatic device from altering the regulation of the generator upon such variations in current as result from changes in the number of cars in the train and in the number of 35 lamps in operation.

The accompanying drawing illustrates a system 40 which will be explained for the purpose of disclosing the present invention. It will of course be understood that the system illustrated in said drawing may be changed in many ways without departing from the invention, 45 and, furthermore, that the drawing illustrates merely sufficient features of the system to disclose the invention.

The generator which furnishes the current to light the cars is preferably arranged upon 50 the tender of the locomotive; but it may be located elsewhere upon the train. It is preferably provided with an armature 1 and a shunt field-winding 2, and the armature is

preferably geared to an axle. The field-circuit of the generator is preferably provided 55 with a variable resistance 3 for regulating the strength of the current in the field-winding 2. The resistance 3 may be composed of a series of resistance-plates, of carbon or other suitable material, said plates being placed in contact with each other and arranged between a stationary terminal block 4 and a movable terminal block 5. The position of the stationary terminal block may be adjusted by a screw 6. The movable terminal block is preferably 60 mounted upon a plunger 7. The resistance-plates are caused to press together by a spring 8, and the tension of said spring may be adjusted by a screw 9. The pressure between the resistance-plates is regulated by an electromagnet 10, which attracts the plunger 7. Upon an increase in the strength of said magnet 70 the pressure between the resistance-plates will be decreased, thereby increasing the resistance in the field-circuit of the generator, 75 and likewise upon a decrease in the strength of said magnet the pressure between said plates will be increased, thereby decreasing the resistance in the field-circuit of the generator.

Through the train may extend a train-line, 80 which is preferably composed of conductors 11, 12, and 13. The conductors 12 and 13 are preferably connected to the generator by supply-mains 14 and 15 at the forward end of the train, and the conductors 11 and 12 are preferably 85 connected to each other at the rear end of the train.

The stationary terminal block 4 is preferably connected to one terminal of the generator, and the movable terminal block 5 and 90 the shunt field-winding 2 are preferably connected to the other terminal of the generator, thereby placing the variable resistance 3 and the shunt field-winding 2 in series with each other and in shunt with the armature 1. The 95 electromagnet 10, which controls the variable resistances, may be arranged in the main circuit in series with the armature of the generator.

The equipment which is provided for each 100 car will now be explained. The drawing illustrates the equipments for two cars, and as both equipments are alike reference will be made to a single car in explaining the same.

Each car is preferably provided with a storage battery 16 and translating devices or lamps 105

17. The storage battery and the lamps are connected to a local circuit composed of conductors 19 and 20 and extending across the train-line, said storage battery being arranged 5 in one parallel branch of said local circuit and said lamps in another. As the length of the circuit between the generator and each local circuit is the same, equal voltages will be impressed upon the local circuits.

18. The lamp branch of the local circuit is preferably provided with a switch 20, by which the circuit of the lamps may be opened and closed. The local circuit is preferably provided with an automatic switch for connecting the storage battery and the lamps to the generator and disconnecting the same therefrom. The automatic switch may be provided with stationary contacts 21 and 22 and a movable contact 23. The movable contact 15 is preferably carried by a plunger 24, which is actuated by electric magnetic windings 25 and 26 to operate the switch. The winding 25 is preferably arranged across the local circuit between the switch-contacts and the train-line, and the winding 26 is preferably arranged in the local circuit in series with the switch-contacts and the storage battery. The shunt-winding 25 will cause the switch to close whenever the voltage of the generator equals that 25 of the storage battery, and while the switch remains closed the series winding 26 will be energized by current in the local circuit. So long as the generator sends current through the local circuit the series winding 26 will 30 assist the shunt-winding 25 in keeping the movable contact firmly in engagement with the stationary contacts; but whenever the storage battery sends current through the local circuit, as occurs when the voltage of the generator falls below that of said battery, the series winding will oppose the shunt-winding, and thereby cause the switch to open.

When the generator is in operation, current will flow from the supply-main 14, through 45 train-line 12, to train-line 11. Thence it will flow dividingly through the local circuits, and finally it will reunite in train-line 13 and flow through supply-main 15 and electromagnet 10. If the voltage of the generator be substantially equal to that of the storage battery, the generator and the storage battery will coöperate in furnishing the current for 50 operating the lamps, but if it be greater than that of the storage battery the generator will furnish the entire current for operating the lamps, and, in addition, it will furnish current for charging the storage battery. It being assumed that the latter condition exists, current will flow in the local circuits 55 from the local main 19, through switch-contacts 21, 23, and 22, thence dividingly through the battery branch and the lamp branch of the local circuit to the local main 18. When the generator becomes inoperative, the automatic 60 switch will open, and thus prevent the stor-

age battery from discharging current unto the train-line, and the lamps will then be operated by current from the storage battery. Upon an increase in the speed of the armature 1 the current in the electromagnet 10 will 70 be increased, and then the resistance 3 will be increased, and thereby cause the strength of the field-winding 2 to be decreased, and likewise upon a decrease in the speed of said armature the current in the said magnet will be 75 decreased, and then said resistance will be decreased, and thereby cause the strength of the field-winding to be increased. The strength of the field-winding 2 being thus varied inversely as the speed of the armature 1 varies, 80 the generator will be regulated to confine the output thereof within prearranged limits notwithstanding the wide variations in speed to which it is subjected. Inasmuch as the current for charging the storage battery will increase in almost direct proportion to the rise in voltage of the generator above the normal voltage of said battery, the electromagnet 10 will be subjected to considerable variations in current upon slight variations in the speed 85 of the generator, and in consequence it will be very effective in performing its functions. It will of course be understood that various forms of rheostatic devices may be employed to regulate the generator and that the same 90 may operate in various ways.

From the local circuit of each car to one of the terminals of the generator extends a shunt-circuit 27, which passes around the electromagnet 10. It is preferably provided with a variable resistance 28, which may be composed of a series of resistance-plates of carbon or other suitable material. The resistance-plates are placed in contact, and the pressure between the same is regulated by 100 an electromagnet 29, which attracts the plunger 30. The electromagnet 29 is preferably arranged in the lamp branch of the local circuit.

The current which the generator delivers 110 depends upon the number of cars in the train and the number of translating devices in operation. If the number of cars be increased, the output of the generator will increase, and likewise if the number of cars be decreased, 115 the output of the generator will decrease. Moreover, if the number of lamps in operation in any car be increased, the output of the generator will increase, and likewise if the number of said lamps be decreased the output of the generator will decrease. The generator will therefore deliver sufficient current 120 to supply all demands. It may be assumed where there are two cars in the train, as illustrated in the drawing, that the generator delivers seventy amperes, thirty-five amperes being distributed to each car. Upon adding a car to the train the output of the generator will increase to one hundred and five amperes, 125 and upon taking one away from the train it 130

will decrease to thirty-five amperes. It may be further assumed that in each car twenty amperes are consumed by the lamps and fifteen amperes are delivered to the storage battery. Upon increasing the number of lamps in operation until thirty-five amperes are consumed thereby the output of the generator will increase until fifty amperes are distributed between the storage battery and the lamps. The current for charging the storage battery will therefore remain fifteen amperes, notwithstanding the change in the current consumed by the lamps. When the number of cars in the train is changed, an additional parallel shunt-circuit 27 will be placed around the electromagnet 10 for each car which is added to the train, or one parallel shunt-circuit will be removed from around said magnet for each car which is taken away from the train. These changes in the number of parallel shunt-circuits will so change the portion of the output of the generator which is carried around the electromagnet 10 that no substantial change will take place in the current in said magnet. Whenever the number of lamps in operation in any car is increased, the current in the electromagnet 29 will increase, and thereby cause the resistance 28 to be decreased. Likewise whenever the number of lamps in operation in any car is decreased the current in said magnet will decrease, and thereby cause the resistance 28 to be increased. These variations in the resistance 28 will cause the current diverted from the magnet 10 to so vary that no substantial variation will take place in the current in said magnet. The current in the electromagnet 10 will therefore remain substantially constant so long as the speed of the generator remains constant, notwithstanding changes in the number of cars in the train and in the number of translating devices in operation. If said magnet were subjected to variations in current upon changes in the number of cars in the train and in the number of translating devices in operation, it would cause the variable resistance 3 to so alter the strength of the field-winding 2 that the generator would be incapable of delivering sufficient current for a larger number of cars, and it would perhaps deliver excessive current for a lesser number of cars.

It will be understood that various means may be employed to regulate or limit the voltage impressed upon the lamps.

Having thus described my invention, what I claim, and desire to secure by Letters Patent, is—

1. In a train-lighting system, in combination, a generator driven at a variable speed, a storage battery and translating devices carried upon each of a plurality of units of the train and connected to said generator, an automatic rheostatic device for regulating said generator to confine the output thereof within pre-

arranged limits, an electromagnet for controlling the operation of said device, said magnet being arranged in circuit to be subjected to variations in current upon variations in the speed of said generator, and means for preventing said magnet from causing said device to alter the regulations of said generator upon changes in the number of cars in the train and in the number of translating devices in operation in any car. 75

2. In a train-lighting system, in combination, a generator driven at a variable speed and provided with a shunt field-winding, a storage battery and translating devices carried upon each of a plurality of units of the train and connected to said generator, a variable resistance arranged in the field-circuit of said generator, an electromagnet for varying said resistances to regulate said generator and thereby confine the output thereof within pre-arranged limits, said magnet being arranged in circuits so as to be subjected to variations in current upon variations in the speed of said generator, and means for preventing said magnet from being subjected to variations in current upon variations in the output of said generator resulting from changes in the number of cars in the train and in the number of translating devices in operation in any car. 80 85

3. In a train-lighting system, in combination, a generator driven at a variable speed, a storage battery and translating devices carried upon each of a plurality of units of the train, means for automatically connecting said storage batteries and said lamps to said generator and disconnecting the same therefrom, an automatic rheostatic device for regulating said generator to confine the output thereof within prearranged limits, an electromagnet for controlling the operation of said device and arranged in circuit to be subjected to variations in current upon variations in the speed of said generator, and means for preventing said magnet from causing said device to alter the regulation of the generator upon changes in the number of cars in the train and in the number of translating devices in operation in any car. 90 100 105 110

4. In a train-lighting system, in combination, a generator driven at a variable speed, a storage battery and translating devices carried upon each of a plurality of units of the train, means for automatically connecting said storage batteries and translating devices to said generator and disconnecting the same therefrom, a variable resistance arranged in the field-circuit of the said generator, an electromagnet for varying said resistance to regulate said generator and thereby confine the output thereof within prearranged limits, the means for preventing said magnet from being subjected to variations in current upon changes in the number of cars in the train and in the number of translating devices in operation in any car. 115 120 125 130

5. In a train-lighting system, in combination, a generator driven at a variable speed, a main circuit extending from said generator, a storage battery and translating device carried 5 upon each of a plurality of units of the train and connected to said main circuit, an automatic rheostatic device for regulating the generator to confine the output thereof within prearranged limits, a series electric magnet 10 for controlling the operation of said device, said magnet being arranged in said main circuit, and means for preventing said magnet from being subjected to variations in current upon changes in the number of cars in the train 15 and in the number of translating devices in operation in any car.

6. In a train-lighting system, in combination, a generator driven at a variable speed, a storage battery and translating devices carried 20 upon each of a plurality of units of the train and connected to said generator, an automatic rheostatic device for regulating said generator to confine the output thereof within prearranged limits, an electromagnet for controlling 25 the operation of said device, said magnet being arranged in circuit to be subjected to variations in current upon variations in the speed of said generator, a shunt-circuit extending from each of said units and passing 30 around said electromagnet, a variable resistance arranged in each shunt-circuit, and means for controlling the resistance of each shunt-circuit.

7. In a train-lighting system, in combination, a generator driven at a variable speed, an automatic rheostatic device for regulating said generator to confine the output thereof within prearranged limits, an electromagnet for controlling the operation of said device, said 35 magnet being arranged in circuit to be subjected to variations in current upon variations in the speed of said generator, a storage battery and translating devices carried upon each 40 of a plurality of units of the train and connected to said generator, a shunt-circuit extending from each of said units and passing around said magnet, and means for varying the resistance of said shunt-circuits upon variations in the current consumed by said translating devices.

8. In a train-lighting system, in combination, a generator driven at a variable speed, a main circuit extending from said generator, a local circuit arranged upon each of a plurality of units of the train, a storage battery and translating devices connected to each local circuit, an automatic rheostatic device for regulating said generator to confine the output thereof within prearranged limits, a series 55 electromagnet for controlling the operation of said rheostatic device, said magnet being arranged in said main circuit, a parallel shunt-circuit extending from each local circuit and passing around said magnet, and means for 60 automatically varying the resistance of said 65

shunt-circuits upon variations in the current consumed by said translating devices.

9. In a train-lighting system, in combination, a generator driven at a variable speed and carried upon one of the units of the train, 70 an automatic rheostatic device for regulating said generator to confine the output thereof within prearranged limits, said device being carried upon the same unit of the train as said generator, an electromagnet for controlling 75 the operation of said device, said magnet being arranged in circuit to be subjected to variations in current upon variations in the speed of said generator, a storage battery and lamps carried upon another unit of the train 80 and connected in circuit with said generator, said battery being arranged in one parallel branch circuit and said lamps in another, a shunt-circuit extending from the last-mentioned unit to the first-mentioned unit and 85 passing around said magnet, a variable resistance arranged in said shunt-circuit, and an electromagnet arranged in the lamp branch circuit and controlling said resistance.

10. In a train-lighting system, in combination, a generator driven at a variable speed and carried upon one of the units of the train, 90 a main circuit extending from said generator, an automatic rheostatic device for regulating said generator to confine the output thereof 95 within prearranged limits, said device being arranged upon the same unit of the train as said generator, a series electromagnet for controlling the operation of said rheostatic device, said magnet being arranged in said 100 main circuit, a local circuit arranged upon another unit of the train, a storage battery and lamps arranged in said local circuit, said storage battery being arranged in one parallel branch of said local circuit and said lamps 105 in another, a shunt-circuit extending from said local circuit and passing around said magnet, a variable resistance arranged in said shunt-circuit, and an electromagnet for controlling 110 said variable resistance and arranged in the lamp branch of said local circuit.

11. In a train-lighting system, in combination, a generator driven at a variable speed and carried upon one of the units of the train, 115 an automatic rheostatic device for regulating said generator to confine the output thereof within prearranged limits, said device being carried upon the same unit of the train as said generator, a series electromagnet for controlling 120 the operation of said rheostatic device, said magnet being arranged in said main circuit, a local circuit arranged upon another unit of the train, a storage battery and lamps connected to said local circuit, said storage battery being arranged in one parallel branch 125 of said local circuit and said translating devices in another, an automatic switch for connecting said storage battery and said translating devices to said generator and disconnecting the same therefrom, a shunt-circuit 130

extending from said local circuit and passing around said magnet, a variable resistance arranged in said shunt-circuit, and an electromagnet arranged in the lamp branch circuit 5 and controlling said variable resistance.

12. In a train-lighting system, in combination, a generator driven at a variable speed, an automatic rheostatic device for regulating said generator to confine the output thereof 10 within prearranged limits, an electromagnet for controlling the operation of said rheostatic device, said magnet being arranged in circuit to be subjected to variations in current upon variations in the speed of said generator, a storage battery and lamps carried upon each of a plurality of units of the train, said storage battery being arranged in one parallel branch circuit and said lamps in another, a parallel shunt-circuit extending from 15 each of said units and passing around said magnet, a variable resistance arranged in each shunt-circuit, and an electromagnet arranged in each lamp branch circuit and controlling the variable resistance upon the unit of the 20 train therewith.

13. In a train-lighting system, in combination, a generator driven at a variable speed, a main circuit extending from said generator, an automatic rheostatic device for regulating 25 said generator to confine the output thereof within prearranged limits, a series electromagnet for controlling the operation of said rheostatic device, said magnet being arranged in said main circuit, a local circuit arranged 30 upon each of a plurality of units of the train and connected to said main circuit, a storage battery and lamps arranged in each local circuit, said storage battery being arranged in one parallel branch of said local circuit and 35 40 said lamps in another, a shunt-circuit extending from each local circuit and passing around said magnet, a variable resistance arranged in each shunt-circuit, and an electromagnet arranged in the lamp branch of each local 45 circuit and controlling the variable resistance upon the unit of the train therewith.

14. In a train-lighting system, in combination, a generator driven at a variable speed, a main circuit extending from said generator, 50 a variable resistance arranged in the field-circuit of said generator, a series electromagnet for varying said resistance to regulate said generator, and thereby confine the output thereof within prearranged limits, said 55 magnet being arranged in said main circuit, a local circuit arranged upon each of a plurality of units of the train and connected to said main circuit, a storage battery and lamps

arranged in each local circuit, said storage battery being arranged in one parallel branch 60 of said local circuit and said lamps in another, a shunt-circuit extending from each local circuit and passing around said magnet, a variable resistance arranged in said shunt-circuit, and an electromagnet arranged in the lamp 65 branch of each local circuit and controlling the variable resistance upon the unit of the train therewith.

15. In a train-lighting system, in combination, a generator driven at a variable speed 70 and carried upon the tender of the locomotive, an automatic rheostatic device for regulating said generator to confine the output thereof within prearranged limits, said device being carried upon said tender, an electromagnet for controlling the operation of said rheostatic device and arranged in circuit to respond to variations in current upon variations in the speed of said generator, a storage battery and lamps carried upon a car, 75 said storage battery being arranged in one parallel branch circuit and said lamps in another, a shunt-circuit extending from said car and passing around said magnet, a variable resistance arranged in said shunt-circuit, and 80 an electromagnet for controlling said variable resistance, said magnet being arranged in the lamp branch circuit.

16. In a train-lighting system, in combination, a generator driven at a variable speed, 90 an automatic rheostatic device for regulating said generator to confine the output thereof within prearranged limits, an electromagnet for controlling the operation of said rheostatic device, said magnet being so arranged 95 in circuit as to be subjected to variations in current upon variations in the speed of said generator, a storage battery and translating devices carried upon each of a plurality of units of the train and connected to said generator, a shunt-circuit extending from each of said units, and passing around said field-winding, and means for automatically causing the current in said shunt-circuits to so vary 100 upon variations in the current consumed by 105 said translating devices as to prevent substantial variations in the current in said magnet.

In witness whereof I have hereunto subscribed my name in the presence of two witnesses. 110
